IGNITION SYSTEM.

1,219,704.

Specification of Letters Patent.

Patented Mar. 20, 1917.

Application filed September 4, 1913, Serial No. 788,089. Renewed August 16, 1916. Serial No. 115,332.

To all whom it may concern:

Be it known that I, FRANK CONRAD, a citizen of the United States, and a resident of Pittsburgh, in the county of Allegheny and State of Pennsylvania, have invented a new and useful Improvement in Ignition Systems, of which the following is a specification.

My invention relates to ignition systems such as are used in connection with internal combustion engines.

The object of my invention is to provide a system of the character above indicated in which the current is automatically reversed through the interrupted contact members after each operation of the interrupter.

An interrupter, as commonly constructed, comprises a movable and a stationary contact member, each of which is permanently connected to one pole of a battery or magneto, as the case may be. When the contact members are separated to break the primary circuit, an arc follows in which the current always flows from the same contact member to the other. The result is to cause the one contact piece to become pitted because of the surface metal being carried away and to produce projections on the surface of the other contact member because of the metal deposited during the existence of an arc. The efficiency of the interrupter is decreased by the resulting poor electrical contact between the irregular surfaces of its contact members, and the life of the mechanism is correspondingly shortened.

It has been proposed, heretofore, to reverse the electrical connections of the interrupter, but such arrangements operate to reverse not only the electrical connections of the interrupter but also those of the induction coil and other elements of the ignition circuit. It has been found that such arrangements possess a number of disadvantages that are eliminated by a system constructed in accordance with my invention.

A material disadvantage in connection with the arrangements of the prior art resides in the fact that the spark at the electrodes of a spark plug always occurs adjacent to the one or the other of the electrodes depending upon the direction of the currents traversing the primary and secondary circuits. The central electrode of a spark plug consists of a small rod of metal

while the other electrode is either adjacent to, or is constituted by, the outer ring or bushing that is in engagement with the engine cylinder.

When the spark occurs adjacent to the larger body of metal, it is cooled much more rapidly and hence it is of lower heat intensity and of shorter duration than one occurring adjacent to the central electrode. The reversal of the current through the primary coil after each operation of the interrupter causes alternate ignition sparks to be produced adjacent to the outer electrode of the spark plug. Accordingly, one-half of the sparks are of less heat intensity than the other half and uniformity of operation of the engine is not possible.

I provide a system in which the electrical connection of the interrupter contact members are automatically reversed after each operation. The tendency to transfer metal from one contact member to the other is thus neutralized and the result is not only to materially lengthen the life of the interrupter, but to increase its efficiency during operation by maintaining a substantially plane surface upon the faces of the contact members.

The reversing switch is so arranged that the electrical connections of the interrupter only are changed, and the current always flows in the same direction through the primary and secondary windings of the induction coil. The central electrodes of the spark plugs are so connected that they constitute the negative electrodes of the air gap and, accordingly, the ignition sparks always occur adjacent to the central electrodes. This arrangement insures that the sparks are of maximum heat value and duration.

In the drawings, Figure 1 is a diagrammatic view of circuits and apparatus embodying my invention. Fig. 2 is an end view, partially in elevation and partially in section, of interrupter mechanism. Fig. 3 is a sectional view taken on line III—III of Fig. 2.

Referring particularly to Fig. 1, an ignition system comprises a source of current which may be either a magneto or a battery. In the present instance, a battery 1 is connected in series with the primary winding 2 of an induction coil 3 and with a resistor 4 which may comprise a resistor unit of nichrome wire or other suitable material.

The positive terminal of the battery is permanently connected to a curved contact segment 5 and the negative terminal of the battery is connected to a similar segment 6. 5 A condenser 7 is connected in parallel with the battery.

The secondary circuit of the ignition system comprises the secondary winding 8 of the induction coil 3, one terminal of the 10 winding being connected to the rotatable arm 9 of a distributor 10 and the other terminal grounded as shown. The distributor is provided with four contact segments 11 which are each connected to a spark plug 12.

15 Referring now to Figs. 2 and 3, an interrupter 13 comprises a stationary supporting member 14 which may be a portion of the frame of a magneto or other suitable structure. The member 14 comprises an annular 20 flange 15 which is provided with a groove 16. The stationary portion of the interrupter comprises a sleeve 17 that is rotatably supported within the flange 15 and is provided with two oppositely disposed cams 25 18. The outer end of the sleeve 17 is fitted with an insulating disk 19 which supports the contact segments 5 and 6. The segments are oppositely disposed, as diagrammatically shown in Fig. 1, the intervening spaces 30 being occupied by insulating material or suitably insulated metal segments, as desired. A hollow conductor 20, which extends through the disk 19, is connected, at its inner end, to the contact segment 5 by a 35 member 21 and, at its outer end, is provided with a binding screw 22.

A cap 23, which covers the outer end of the interrupter, is provided with a flange portion 24 having a circumferential groove 40 25 upon its inner surface. A locking ring 26 of resilient material occupies the grooves 16 and 25 when the interrupter is assembled and provides a means for permitting relative rotative movement, but not endwise 45 movement, between the cap 23 and the flange 15. The cap 23 is provided with a radial slit 27 which renders it sufficiently resilient to allow the locking ring 26 to be put in place. A clamping screw 28 causes the cap 50 23 to retain its position relative to the flange 15 and to tightly grip the sleeve 17. The cap 23 is provided with an arm 29 to be connected in any suitable manner to the spark lever (not shown) for adjusting the 55 time of the spark.

The rotatable portion of the interrupter comprises a disk 30 which is provided with an inclined boss 31 for connection to the magneto shaft 32 or to any other shaft having a proper speed ratio with the engine shaft (not shown). Two curved members 33 and 34 are supported by, and insulated from, the disk 30 and respectively support a stationary contact member 35 and a lever arm 36 which carries a contact member 37

to coact with the contact member 35. The arm 36 is provided, at its free end, with a fiber bearing block 38 which engages the cams 18 in succession to rock the arm about its pivotal support indicated at 39 and against the tension of a spring 40. The stationary contact member 35 is electrically connected, through the curved member 33, to an axially disposed spring-pressed brush 41. The movable contact member 37 is connected, through the arm 36 and the curved member 34, to a similarly disposed brush 42 carried by the member 34. The brushes 41 and 42 are placed 180° apart so that, when one of them engages one of the contact segments 5 and 6, the other brush engages the other and oppositely disposed contact segment. As the shaft 32 rotates, each brush engages the several contact segments in succession and thus the connections are reversed twice during each revolution of the shaft.

While the electrical connections, as illustrated in the diagram of Fig. 1, are indicated as being entirely metallic, in actual practice, the contact segment 6 will be grounded to the cap 23 by means of a screw 43, Fig. 3, and one terminal of the battery and condenser will be grounded.

It may be assumed that the shaft 32 is rotating in a counter clockwise direction (Fig. 2) and that the block 38 is in a position intermediate the cams 18 so that the contact members 35 and 37 are connected. It may be assumed further that the brushes 41 and 42 engage the contact segments 5 and 6, respectively. Current then flows through the primary circuit which extends from the positive terminal of the battery 1 through the resistor 4, contact segment 5, brush 41, curved member 33, contact members 35 and 37, lever arm 36, curved member 31, brush 42, contact segment 6 and primary coil 2, to the negative terminal of the battery. When the bearing block 38 engages the inclined surface 43 of one of the cams 18, the arm 36 is moved about its pivot to separate the contact members 35 and 37 and thereby break the primary circuit. An electromotive force of high value is induced in the secondary 115 circuit, and a spark occurs across the terminals of the spark plug that is connected to the distributor arm 9.

The further rotation of the shaft 32 causes the brushes 41 and 42 to be carried out of engagement with the respective contact segments 5 and 6 and to engage the opposite segment. The primary circuit will again be closed when the block 38 moves off the cam 18. Current then flows in a reversed direction between the brushes 41 and 42. When the contact members are again disengaged by the block 38 striking the next cam 18, the arc which follows between the contact members 35 and 37 will be produced by a 130

current having a direction opposite to that of the preceding arc, and an opposite effect will thereby be produced upon the respective interrupter contacts.

5. The time of the spark may be varied by means of the arm 29 which is connected to the sparking control lever (not shown). The adjustment of the angular position of the cap 23 and the sleeve 17 causes the cams 10 to be engaged by the block 38 at an earlier or later period in the engine stroke, according to the direction of movement of the arm 29.

While a condenser is employed to reduce the sparking, it is essential to employ an arrangement of the character above described to insure the efficient operation and durability of the interrupter mechanism. The high cost of materials, such as platinum and 20 iridium, which are employed in the manufacture of contact members, render it desirable to prolong the life of these parts. The advantages of an ignition system which requires little attention and few or no 25 repairs will be appreciated by those skilled in the art to which my invention appertains.

While I have shown a specific form of mechanism by means of which my invention is exemplified, it is understood that the details thereof are illustrative only and not limitations, other than as defined in the appended claims.

I claim as my invention:

1. In an ignition mechanism, the combination with a source of current, and a pair of relatively movable contact members, of means for intermittently connecting said contact members in circuit with said source and means for effecting the engagement and disengagement of said contact members while they are in circuit with said source.

2. In an ignition mechanism, the combination with a source of current, and a pair of contact segments connected to the terminals 45 of said source, of a pair of relatively movable contact members, means for connecting said members to said segments successively, and means for effecting the engagement and disengagement of said contact members 50 while the latter are connected to said source.

3. In an ignition system, the combination with a source of current, and contact segments connected to the terminals of said source, a plurality of movably mounted contact members, means for controlling the relative positions of said contact members, means

connected to said contact members for engaging said contact segments successively, and means for simultaneously adjusting the angular positions of said controlling means 60 and said segments.

4. In an ignition system, the combination with a source of current, and contact elements connected to the terminals of said source, of a rotatable member, a pair of relatively movable contact members carried by said rotatable member, relatively stationary members for effecting the engagement and disengagement of said contact members, means for connecting said contact members 70 to said contact elements, and means for simultaneously adjusting the angular position of said contact elements and said stationary members.

5. In an ignition system, the combination 75 with a coil, a source of current and an interrupter for controlling a circuit comprising said coil and said source, of a switch for reversing the connections of said source while said circuit is broken at said interrupter. 80

6. The combination with a source of current, an interrupter and a coil in circuit with said source and said interrupter, of means for reversing the electrical connections of said interrupter only. 85

7. The combination with a source of current, an interrupter and a coil in circuit with said source and said interrupter, of means for periodically reversing the electrical connections of said interrupter without altering 90 the connections of the remainder of the circuit.

8. The combination with a source of current, an interrupter and a coil in circuit with said source and said interrupter, of a reversing 95 switch rotatable with said interrupter for reversing the connections of the interrupter only for each succeeding operation.

9. The combination with a source of current and a coil, of a unitary mechanism 100 comprising an interrupter and a reversing switch in circuit with said source and said coil, said switch being operable to periodically reverse the electrical connections of said interrupter only. 105

In testimony whereof, I have hereunto subscribed my name this 30th day of August, 1913.

FRANK CONRAD.
